Inventor:

George Wade,
By his Attorney, G. H. May

UNITED STATES PATENT OFFICE.

GEORGE WADE, OF NEWARK, NEW JERSEY.

BELT BUCKLE.

1,426,794.

Specification of Letters Patent. Patented Aug. 22, 1922.

Application filed October 21, 1921. Serial No. 509,306.

To all whom it may concern:

Be it known that I, GEORGE WADE, a citizen of the United States, and a resident of the city of Newark, county of Essex, and State of New Jersey, have invented certain Improvements in Belt Buckles, of which the following is a specification.

While applicable to belt buckles generally, my invention is designed more particularly for incorporation with the buckles on waist belts intended for masculine wear, and used for the purpose of sustaining the trousers in position in the absence of suspenders, or in conjunction therewith, as the case may be, the object of my improvement being primarily to prevent the belt, when in position on the person, from slipping or working above the waist-band of the trousers, thereby obviating the discomfort and indecorous appearance involved in such lack of coincidence between trouser waist band and belt, as hereinafter more fully set forth.

To this end, my invention consists, primarily and essentially in providing a waist belt buckle with an inverted hook member adapted for insertion in the usual button hole positioned on the front over-lap of the trousers waist band for engagement with the button situated on the under lap of said waist band, as is customary with garments of this character,—the belt buckle hook thus provided, when tucked into said waist band button hole, effectually counter-acting any tendency of the belt to slip or work off and above the trousers waist band, and preserving the alignment between said waist band and belt under ordinary conditions of use, so that a symmetrical and proper co-relationship of parts is maintained.

In the accompanying drawings:

Fig. 1, is a rear view of a buckle, of the clamp-jaw type, provided with my inverted retaining hook, and as applied to the over-lapping ends of a waist belt;

Fig. 2, is a section taken upon plane of line 2—2, Fig. 1;

Fig. 3, is a view similar to Fig. 1, showing the invention as incorporated with a belt buckle of the loop type;

Fig. 4, is a section taken upon plane of line 4—4, Fig. 3;

Fig. 5, is a front view of the upper frontal portion of a pair of trousers, or nether outer garment, with my retaining hook shown in dotted lines and as in engagement with the

waist band button hole, the belt and buckle being indicated by dotted lines;

Fig. 6, is a sectional view of the parts indicated in Fig. 5, and taken upon plane 60 of line 6—6 thereof;

Fig. 7, is a detail view, on an enlarged scale, of a form of retaining hook adapted for incorporation in a belt buckle, and for use for the purpose herein designated.

It is to be understood in this connection that while I herein show and describe my invention as adapted for use in conjunction with men's trousers, as the main field of utility, I do not limit my improved belt 70 buckle to such use, as it may be utilized in combination with belts for feminine wear, as for instance where waist belts are used in association with the waist bands of 75 skirts, &c.

With this understanding, B, represents a waist belt of any kind, or for any appropriate purpose, b, being the overlap end and b', the under-lap end thereof. The clasp buckle C, shown in Figs. 1 and 2 of 80 the drawings, is of the serrated clamp type, being formed with the pivotally attached clamping jaw c, for effecting connection with the under lap end b', of the belt; whereas in Figs. 3 and 4, the buckle is of 85 the loop type, being formed with a loop c', for attachment to the under lap end b', of the belt B. As a matter of fact the form of clasp buckle C, is of secondary importance, as I do not limit myself to any special 90 form or construction of clasp buckle C, provided that used is adapted to receive and afford support for my inverted retainer hook H.

The latter also may be varied in configuration and structure without departing from the spirit and intent of my invention in this respect, the form shown in the drawings by way of exemplification, consisting of a metallic wire of suitable diameter and 100 strength bent permanently into shape to form the insert or hook proper h, and the shank portions h', h', the ends of which latter are journaled, as at h², h², (see particularly Fig. 7) to fit into bearing holes 105 formed for the purpose in the top and bottom flanges c², c², of the buckle B. By thus pivotally attaching the retaining hook H, to the frame of the clasp buckle C, I facilitate the manipulation of said hook, and 110 adapt it to conform to requirements of use.

As will be noted, the insert portion h is

disposed at an angle of substantially 45 degrees from the body of the hook so that in use, when inserted in the button-hole, the waistband will rest in the angle of the hook, 5 and displacement thereof is prevented.

In Figs. 5 and 6 of the drawings, I illustrate the practical application of my improved buckle and its retainer hook to the 10 waist band of a nether garment G, the waist band of which is formed with a button hole g' , for the accommodation of a button g^2 , as shown particularly in Fig. 5, by reference to which it will be seen that the 15 insert portion n , of my retaining hook H, protrudes upward into and through said button hole g' , and hence will prevent the slipping upward of the belt above and away from the waist band g , of the garment G.

By this means a symmetrical alignment 20 and appearance of the parts involved is assured,—and the comfort and convenience of the wearer enhanced,—it being a well known fact that the slipping and necessary and frequent readjustment of the ordinary waist 25 belt as heretofore used, is a constant source of annoyance to the wearer.

What I claim as my invention and desire to secure by Letters Patent, is,

1. A belt buckle formed with a retaining hook of the character designated having an 30 insert portion disposed at an angle of substantially 45° from its junction with the body of the hook to extend substantially across the belt and adapted to engage to a considerable extent in the button-hole of 35 the waist-band of a garment.

2. A belt buckle formed with a pivotally-mounted retaining hook of the character designated having an insert portion extending from a point in proximity to one 40 of the pivot members of the said hook disposed at an angle of substantially 45° from its junction with the body of the hook to extend substantially across the belt and adapted to engage to a considerable extent 45 in the button-hole of the waist-band of a garment.

GEORGE WADE.
